CARD-CONTROLLED IMPRESSION
MECHANISM

Edward G. Watkins, Gardner, Mass., assignor to
Simplex Time Recorder Co., Gardner, Mass., a
corporation of Massachusetts

Application November 22, 1937, Serial No. 175,796

8 Claims. (Cl. 101—297)

This invention relates to recording machines, such as time recorders or time stamps, in which an impression device in the form of a hammer or platen is actuated by electro-magnetic means 5 to print a time record or other data.

It is desirable that such a machine be conveniently operable by the hand which inserts the card, and machines have been devised in which mere insertion of the record card initiates 10 operation of the impression mechanism.

It is the general object of my invention to provide an improved construction in such machines, whereby insertion of a card causes the circuit of the actuating magnet or solenoid to be 15 closed and to be thereafter opened, entirely independent of the operation of the impression mechanism or of any other part of the machine.

To the attainment of this object, I preferably provide mechanism which is set in operation by 20 card insertion and which thereafter acts independently to successively close and open the electro-magnetic circuit.

My invention further relates to arrangements and combinations of parts which will be herein- 25 after described and more particularly pointed out in the appended claims.

A preferred form of the invention is shown in the drawings, in which

Fig. 1 is a front elevation of my improved im- 30 pression mechanism;

Fig. 2 is a sectional side elevation, taken along the line 2—2 in Fig. 1;

Figs. 3, 4 and 5 are front elevations of the 35 circuit-controlling device shown in Fig. 1 but in different and successive operative positions;

Fig. 6 is a front elevation of certain parts of the impression mechanism; and

Fig. 7 is a detail side elevation, looking in the direction of the arrow 7 in Fig. 6.

Referring to the drawings, I have shown my invention embodied in a workman's card time recorder having type wheels 10 driven by a clock movement or other time mechanism (not shown) and presenting a printing face adjacent a card 40 chute 11. The recorder is indicated as being of the type in which the card is variably positioned vertically by a card support 12, slideable in grooves 14 in the sides of the card chute 11.

The card support is shown as being connected 50 by a link 15 to the front end of a lever 16, pivoted at 17 and adapted to be actuated by a cam or other suitable mechanism, time controlled or otherwise, not shown herein and forming no part of my present invention.

55 A hammer 18 having a flexible arm 19 is

mounted on a rock shaft 20 in such position that it will engage the card in substantial alignment with the printing face of the type wheels 10. The shaft 20 is supported in fixed bearings in the frame of the machine and may be provided with an arm 21 (Figs 6 and 7) extending into an opening in the lower end of a plunger 22 vertically slideable in a solenoid coil 23. The terminals 24 and 25 of the coil 23 are connected to binding screws 26 and 27 in the rear part of the re- 11 recorder.

For a more complete description of the hammer mechanism, reference is made to the prior application of Watkins and Dell, Serial No. 64,246, filed February 17, 1936.

I will now describe the improved mechanism by which operation of the solenoid 23 and of the associated hammer mechanism is initiated by insertion of a card in the card chute 11.

A bell crank 30 is pivoted at 31 on the card support 12 and has a laterally offset portion 32 overlying said card support. A fixed contact 33 is mounted on a bracket 34 secured to the card support 12 and a movable contact 35 is mounted on a flexible arm 36 fixed to a bracket 37, which in turn is also secured to the card support 12. A wire 38 is connected to a binding screw 31a on the bracket 37 and to a binding screw 39 on a plate 40 fixed to the card support 12. The bracket 34 and the plate 40 are connected by 31 wires 41 and 42 to the binding screws 26 and 27 previously described. The brackets 34 and 37 and the plate 40 and the screws therein are electrically insulated from the card support 12.

The wires 41 and 42 are preferably secured to 34 the link 15 by a clip 44, and are provided with sufficient slack so that they may be easily swung upward or downward with the card support.

A star wheel 50 is loosely secured by a pivot stud 51 to the card support 12, and a ratchet 40 wheel 52 is fixed to the star wheel 50.

A feed lever 54 is pivoted at 55 on the card support 12 and is provided with a spring 56 which normally holds the lever 54 against a stop pin 57. A feed pawl 60 for the ratchet wheel 52 is pivoted at 61 to the upper end of the feed lever 54 and is yieldingly drawn downward against a stop 62 by a spring 63 which connects pins in the sides of the lever 54 and pawl 60.

A latch 70 is pivoted at 71 to the lower end of 50 the bell crank 30 and at its outer end is provided with a hook adapted to engage the lower end of the feed lever 54. A spring 72 is secured to pins in the bell crank 30 and latch 70 respectively and tends to swing the latch 70 upward. 51

The latch 70 has a cam portion 75 on its upper face adapted to engage a stop pin 76 under certain conditions.

5 A spring 80 acts to move the bell crank 30 to the position shown in Fig. 1, in which it engages a stop pin 81. The flexible contact arm 36 has a projection 85 positioned for engagement by the teeth of the star wheel 50. Either the projection 85 or the star wheel 50 should be of non-conducting material.

10 Having described the construction of my improved mechanism, I will now describe the operation thereof. The normal position of the parts is as shown in Fig. 1, with the offset portion 32 of the bell crank 30 lifted substantially above the upper edge of the card support 12. When a card is inserted and pressed lightly downward, the offset portion 32 is pressed down against the upper edge of the card support 12 and the lower end of 15 the bell crank 30 is swung to the left in Fig. 1, thereby moving the feed lever 54 and feed pawl 60 to the position shown in Fig. 3. The feed pawl 60 is thereby moved rearward one tooth relative to the ratchet wheel 52 and star wheel 50.

20 15 As the parts reach this position, the cam portion 75 of the latch 70 engages the stop pin 76 and is forced downward to release the feed lever 54, which is thereupon moved to the position shown in Fig. 1 by the tension of the spring 56.

25 20 Such movement of the feed lever advances the ratchet wheel 52 and star wheel 50 counterclockwise by one tooth space. During this advance movement, one point of the star wheel engages the projection 85 on the flexible arm 36, forcing the same downward and causing the contacts 33 and 35 to be engaged as indicated in Fig. 4.

30 25 During the completion of the advance movement of the star wheel, the engaged point of the star wheel is moved beyond the projection 85, and the flexible arm 36 then swings upward, separating the terminals 33 and 35 and breaking the circuit, the parts being then in the position shown in Fig. 5. During the time the circuit was closed, the solenoid coil 23 was energized and a blow was struck by the hammer 18.

35 40 45 When the pressure of the card is removed, the spring 80 restores the bell crank 30 to initial position and moves the latch 70 to the right to clear the pin 76 and to reengage the lower end of the feed lever 54.

50 It thus appears that the operation of the hammer mechanism is initiated by insertion of a card in the card chute and by pressure of the card against the offset portion 32 of the bell crank 30. 55 It further appears that the simple downward displacement of said bell crank causes successive circuit-closing and circuit-breaking operations to take place which are entirely independent of the operation of any other part of the machine.

55 60 65 If for any reason the parts operated by the electro-magnet or solenoid should fail to move, this would have no effect on the closing and opening of the circuit, which events would take place in definite timed relation and regardless of the movement or lack of movement of any other machine part.

70 65 70 While I have shown my invention embodied in a machine in which a movable card support is utilized, it is obvious that my improvements would operate in the same manner in a machine in which the card support was stationary.

75 Having thus described my invention and the advantages thereof, I do not wish to be limited to the details herein disclosed, otherwise than as set forth in the claims, but what I claim is:—

1. In a time recording apparatus comprising a card chute, a card support, printing devices adapted to make a record on a card resting on said support, electro-magnetic means to actuate said printing device to make said record, and an electro-circuit for said means, that improvement which consists in providing mechanism to successively close and open said electric circuit, a spring-operated device to actuate said mechanism, and card-engaged means to tension and then release said device as the card is inserted and seated on said support. 10

2. In a time recording apparatus comprising a card chute, a card support, printing devices adapted to make a record on a card resting on said support, electro-magnetic means to actuate said printing device to make said record, and an electro-circuit for said means, that improvement which consists in providing mechanism to successively close and open said electric circuit, a spring-operated device to actuate said mechanism, and card-engaged means to tension and then release said device as the card is inserted and seated on said support, said mechanism being actuated by said spring-operated device after release thereof by said card-operated means and independently of said electro-magnetic means. 20

25 3. In a time recording apparatus comprising a card chute, a card support, printing devices adapted to make a record on a card resting on said support, electro-magnetic means to actuate said printing device to make said record, and an electro-circuit for said means, that improvement which consists in providing a star wheel effective to successively close and then open said circuit, spring-operated means to advance said star wheel step-by-step, and connections through which insertion of a card in said chute first tensions said spring-operated means and then releases said means to actuate said star wheel independent of 35 said electro-magnetic means. 40

4. In a time recording apparatus comprising a card chute, a card support, printing devices adapted to make a record on a card resting on said support, electro-magnetic means to actuate said printing device to make said record, and an electro-circuit for said means, that improvement which consists in providing a control member movably mounted on said support and having a portion positioned in the path of an inserted card and engaged and moved thereby, and a circuit-closing mechanism set for operation by such engagement and thereafter effective to automatically close and then open said circuit independently of the position of said card, of said member, of said electro-magnetic means, and of any parts actuated thereby. 45 50 55

5. In a time recording apparatus comprising a card chute, a card support, printing devices adapted to make a record on a card resting on said support, electro-magnetic means to actuate said printing device to make said record, and an electro-circuit for said means, that improvement which consists in providing a control member movably mounted on said support and having a portion positioned in the path of an inserted card and engaged and moved thereby, mechanism including a spring-operated member for automatically and successively closing and then opening said electric circuit, and connections between 60 65 70 said control member and said mechanism through which movement of said control member by insertion of a card in said chute first tensions said spring-operated member and then releases said member to actuate said mechanism. 75

6. In a time recording apparatus comprising a card chute, a card support, printing devices adapted to make a record on a card resting on said support, electro-magnetic means to actuate said printing device to make said record, and an electro-circuit for said means, that improvement which consists in providing a control member movably mounted on said support and having a portion positioned in the path of an inserted card and engaged and moved thereby, a rotatable element effective to alternately close and open said circuit, a ratchet wheel rotatable with said element, a feed pawl for said ratchet wheel, a spring to give said pawl a feeding movement, and connections between said control member and said feed pawl through which movement of said control member by insertion of a card in said chute first tensions said spring and then releases said feed pawl to actuate said ratchet wheel and rotatable element.

7. Card-controlled printing mechanism having electro-magnetic actuating means, a member engaged by the edge of the card and movable thereby, a control device for successively closing

and opening the electro-magnetic circuit, and feeding means for said control device rendered operative by card-actuated movement of said card-engaged member, but operation of said feeding means to move said control device to close and thereafter open said circuit taking place only after release of said feeding means by said card-engaged member and independently of said cardengaged member and of said electro-magnetic means and of any parts actuated thereby. 10

8. Card-controlled printing mechanism comprising printing devices having electro-magnetic actuating means, a member engaged by the edge of a card and movable thereby, mechanism for successively closing and opening an electro-circuit for said electro-magnetic means, and connections through which movement of said card-engaged member first sets said mechanism for operation and then releases said mechanism to operate independently to close and thereafter 20 open said circuit without reference to the position of said card-engaged member or of any parts actuated by said electro-magnetic means. 15

EDWARD G. WATKINS.
